Specification for Design.

Patented Oct. 15, 1912.

Application filed February 1, 1912. Serial No. 674,845. Term of patent 14 years.

To all whom it may concern:

Be it known that I, JOHN A. MOORE, a citizen of the United States, residing at Wheeling, in the county of Ohio and State of West Virginia, have invented a new, original, and ornamental Design for Mattocks, of which the following is a specification, reference being had to the accompanying drawing, forming a part thereof.

Figure 1 is a top plan view of a mattock, showing my new design, and Fig. 2 is a side elevation of the same.

I claim:

The ornamental design for a mattock, as shown.

In testimony whereof, I have hereunto affixed my signature in the presence of two subscribing witnesses.

JOHN A. MOORE.
